John F. Livers, Decatur, Ill., assignor to Faries Manufacturing Company, Decatur, Ill., a corporation of Illinois

Application January 4, 1941, Serial No. 97,815

Term of patent 7 years

To all whom it may concern:

Be it known that I, John F. Livers, a citizen of the United States, residing at Decatur, in the county of Macon and State of Illinois, have invented a new, original, and ornamental Design for a Fluorescent Desk Lamp, of which the following is a specification, reference being had to the accompanying drawing, forming part thereof, in which

Fig. 1 is a front elevational view of a fluorescent desk lamp showing my new design.

Fig. 2 is a side elevational view thereof.

Fig. 3 is a sectional view thereof taken on the line 3—3 of Fig. 1.

I claim:

The ornamental design for a fluorescent desk lamp, as shown.

JOHN F. LIVERS.
